(51) **LOC (13) Cl.** **15-03**

CLAIM

(52) **U.S. Cl.**

The ornamental design for an adapter cover for a ground engaging machine implement, as shown and described.

USPC **D15/29; D15/28**

DESCRIPTION

(58) **Field of Classification Search**

USPC D15/11, 28, 29; 37/456, 452, 450, 446,
37/454, 449, 453, 455, 903; 403/379.5,
403/DIG. 1; 111/152; 172/724, 730,
172/766, 770, 771, 721, 713, 699, 772

CPC Y10T 29/49826; Y10T 403/589; Y10T
403/7018; Y10T 403/7075; E02F 9/28;
E02F 9/2825; E02F 9/2833; E02F 9/2866;
E02F 9/2858; E02F 9/2808; E02F 9/2841

See application file for complete search history.

(56) **References Cited**

FIG. 1 is a front perspective view of an adapter cover for a ground engaging machine implement showing our new design;
FIG. 2 is a front view thereof;
FIG. 3 is a rear view thereof;
FIG. 4 is a left side view thereof;
FIG. 5 is a right side view thereof;
FIG. 6 is a top view thereof; and,
FIG. 7 is a bottom view thereof.

The broken lines illustrate structure or features which form no part of the claimed design.
The dot-dash broken lines illustrate boundaries which form no part of the claimed design.
